TUNNELING BY CORE-FORMING AND REMOVAL 5

John C. Haspert and Thomas N. Williamson, Houston, Tex., assignors to Hughes Tool Company, Houston, Tex., a corporation of Delaware

Filed Oct. 11, 1957, Ser. No. 689,593

3 Claims. (Cl. 262—7)

This invention relates to tunneling and has as a primary object the orderly advancement of a tunnel by progressively cutting cores at the heading and effectively removing from the heading all cuttings and cores whereby the tunnel is advanced efficiently.

It is the primary object of the invention to provide method and apparatus for accomplishing this purpose.

Another object is to progressively form a core at a heading, remove cuttings during such operation and simultaneously move core catching means into position about the core so that removal may be quickly effected when a predetermined length of core has been cut.

Still another object is to provide method and apparatus for removing earth material from a heading in large volume core sections.

The invention also contemplates forming a core with its nether portion cut away, the space thus formed being used for clearance for actuating mechanisms and for the progressive entrance of core catching means for handling the core once it has been severed from the heading.

These and other advantages and objects of the invention will be more fully apparent from the following description considered in connection with the accompanying drawings in which:

Fig. 1 is a perspective view of one form of the invention, the component parts being shown in their relative positions when a core of severed earth formation has been withdrawn from the core drill;

Fig. 2 is a schematic diagram showing the core removing mechanism returning to its core receiving position;

Fig. 3 is a schematic diagram showing all equipment in position to advance cutting of the tunnel bore;

Fig. 4 is an enlarged view of the core drill and driving means therefor;

Fig. 5 is a sectional view taken on line 5—5 of Fig. 4;

Fig. 6 is an enlarged sectional detail of the thrust bearing between the core drill and its advancing mechanism;

Fig. 7 is an elevational view taken on line 7—7 of Fig. 4;

Fig. 8 is a sectional view on line 8—8 of Fig. 4;

Fig. 9 shows a modified form of the core and cuttings removing component of the device;

Fig. 10 is a sectional view taken on line 10—10 of Fig. 9;

Fig. 11 is a sectional view taken on line 11—11 of Fig. 9.

The present invention is concerned with a modified coring type of tunneling machine and the embodiment shown in the drawings is shown as comprising a cutter unit 1 and, telescoping therewith, a mobile carrier unit 2 equipped to remove cuttings as formed and to remove successive sections of the core. The entire unit is movable longitudinally of the track 3 as tunneling progresses.

It is to be here noted that the cutter unit 1 is of such size and construction that it will cut in a heading a circular bore of sufficient size that all portions of the device may be readily movable therein. Also such unit cooperatively receives the forward portion of the carrier unit 2

2

so that all formation material removed from the heading is quickly removed from the heading area.

The cutter unit 1 comprises a core type drill 10 having base 11 and barrel 12 with cutter assemblies 13 secured to its forward end. These cutter assemblies as well as those on pilot bit 14 comprise roller cutters of the cone type rotatably mounted upon suitable supports. Inasmuch as such assemblies are well known in the art and do not per se constitute the present invention they are not specifically shown or described herein.

Secured to the interior of the barrel 12 are a plurality of spiral flights 15 (Figs. 4 and 5) having projecting ends 16 it being the purpose of these flights to engage cuttings removed by the cutters and propel such cuttings away from the cutting zone so that carrier equipment hereinafter described will remove the cuttings from the scene of operations. It is to be understood that the radial dimensions of the barrel 12 and the flight 15 are such as to provide adequate clearance within the kerf or annulus cut by the cutter assemblies 13.

A feature of the present invention resides in the use of the pilot bit 14 mounted upon the shaft 20 eccentrically of the barrel 12 so that the core 21 has an arcuate longitudinal portion cut away at its lower side, as best seen in Fig. 1, thus leaving a clearance space 22 at the lower side of the core. This feature of construction and the mode of operation serve multiple functions as will be presently apparent.

Spaced from the base 11 of the core drill 10 is an expandable anchor ring 25 which is expanded by any suitable mechanism such as jack screw 26 so that the ring will form an anchor with the walls of the tunnel being formed. A plurality of packs 27 are mounted on the ring 25 and extend forwardly and engage the base 11 of the core drill. This base includes a guide ring 28 which is likewise expandable by a jack screw 26' (Fig. 4) sufficiently that the core drill 10 is slidably but accurately guided forwardly during the tunneling operation.

The core barrel 12 has an inwardly extending flange 30 at its inner end. The end face of this flange has a raceway which is complementary to a raceway in the base 11 to receive thrust rollers 31 and provide an antifriction thrust bearing between the advancing mechanism, already described, and the core drill assembly 10. A ring gear 32 is mounted on and secured to the inner diameter of the flange 30 and intermeshes with a pinion 33 on the shaft 20 upon which the pilot bit 14 is mounted.

The shaft 20 is journaled in a spider 34 (Fig. 8) which constitutes an integral part of the base 11. In turn a telescopic driving connection is had between the shaft 20 and the hollow shaft 35 of the prime mover 36 mounted as an integral part of the cutter unit 1.

It seems apparent that operation of the prime mover 36 rotates the pilot bit 14 and at the same time effects rotation of the core drill through the pinion 33 and the ring gear 32.

The carrier unit 2 comprises a chassis 38 mounted upon wheels 39 on the track 3, suitable prime mover equipment being provided on the chassis for propulsion thereof and for effecting such other operations as necessary. This unit includes a horizontally extending core catcher member 40 having arcuately extending side flanges 41 and a central arched portion 42. This support is therefore of such configuration as to fit the contour of the lower portion of the core 21 and it moves beneath the core as the entire mechanism moves forward as tunneling progresses.

A second core catcher member 43 is spaced above member 40 and its forward end is coaxial with the drill 10 so that it overlies the core 21 as it is formed. This core catcher member is tiltably mounted upon pintle 44 on the chassis 38. Rearwardly of the pintle is a hydraulic actuator 45 mounted upon the chassis 38 and

operable to move the member 43 so that the core catcher will clamp upon the core 21 at such time as desired by the operator.

In the form of the invention shown in Fig. 1, suitable suction means (not shown) is connected through lines 46 to nozzles 47 which terminate proximate the cutters 13 and at the bottom of the core 21. Hence, cuttings, as formed, are picked up and are transported rearwardly to the trailer 48 whence they can be removed from the zone of operation.

To further describe the disclosed embodiment of the invention and its mode of operation, it is noted that the cutter unit 1 is advanced to the heading 4 at the end of the tunnel 5. The jacks 27 are retracted as shown in Fig. 2, and ring 25 is anchored to the walls of the tunnel by actuation of the jack 26. Carrier unit 2 is then advanced as indicated by the arrow in Fig. 2 until the forward ends of the core catcher members extend substantially the entire length of the barrel 12 and the nozzles 47 are at a point to pick up the cuttings formed by the cutters 13.

Prime mover 36 is then energized to effect rotation of the core drill 10 and the pilot bit 14 whereupon the core 21 is formed as the drill advances. In the meantime the carrier unit 2 advances so that the core enters the core catcher. It is intended that the jacks 27 may be extended such distance that a desired length of core is cut during a single setting of the anchor ring 25. The jack 45 is then actuated to grasp the core 21 for removal. If the core will not dislodge from stress placed thereon by movements of the carrier unit 2, the small shot hole drill 49 mounted on the carrier unit may be operated to drill a shot hole in the core so that a charge can be set off to sever the core from its attachment at the heading. The carrier unit with core and trailer 48 may then be moved from the heading for disposal of the core and cuttings.

Figs. 4 and 9 to 11 show an alternate method of removing the cuttings from the heading. In this modification the cuttings are moved upwardly and rearwardly by the flights 15 as the drill 10 rotates. As these flights move toward their uppermost position the cuttings fall upon a conveyor 50 mounted on brackets 51 on the nether side of the core catcher member 43. The conveyor 50 passes over rollers 52, driven from a suitable source (not shown) and extends rearwardly a sufficient distance that the cuttings are conveyed to and deposited in the trailer 48.

It should be noted that the tunneling apparatus of the invention is such as to enable removal of large core sections from a heading. These sections may be withdrawn a short distance from the heading and disposed of by sideward displacement into pockets formed along the tunnel for this purpose. The core carrier may thus be released for immediate reuse, whereby the carrier is removed from the heading for a minimum of time during

which the drill is reset for the next successive cutting of a core. As cutting progresses the previous cuttings and core may be removed from the tunnel by other suitable means.

Broadly the invention comprehends methods and apparatus for the orderly advancement of a tunnel and the efficient removal of cuttings and cores from the heading.

We claim:

1. In a coring type tunneling machine, a core drill adapted to cut a kerf having an outer diameter substantially equal to the diameter of the desired tunnel bore, a pilot bit mounted to rotate about an axis eccentric to the axis of the core bit and to cut a pilot hole in advance of the core bit, means for driving and advancing said core drill and pilot bit, and core catching means movable with said drill and bit to enter the pilot hole in the core and the kerf opposite the pilot hole to support and move sections of core from within the core bit.
2. In a coring type tunneling machine, a core drill adapted to cut a kerf having an outer diameter substantially equal to the diameter of the desired tunnel bore, a pilot bit mounted to rotate about an axis eccentric to the axis of the core bit and to cut a pilot hole in advance of the core bit, means for driving and advancing said core drill and pilot bit, opposed core catching members movable with said drill and bit to enter the pilot hole in the core and the kerf opposite the pilot hole, and means for moving said members into engagement with the core to support and move sections of core from within the core bit.
3. The method of forming a tunnel comprising progressively drilling a pilot hole along and below the axis of the projected line of the tunnel, forming the tunnel bore by cutting an annular kerf transecting said pilot hole and having an outer diameter substantially equal to that of the desired tunnel bore, simultaneously advancing core catching members within the pilot hole in the core being cut and in the kerf opposite said hole, and thereafter clamping the core between said members and withdrawing the core and members from the heading of the tunnel bore.
